UNITED STATES PATENT OFFICE.

JAMES H. MARDOCK, OF FRUITLAND, IOWA, ASSIGNOR OF ONE-HALF TO
JOHN A. SHOULTZ, OF SAME PLACE.

DESIGN FOR A NAPKIN-HOLDER.

SPECIFICATION forming part of Design No. 33,067, dated August 14, 1900.

Application filed July 13, 1900. Serial No. 23,551. Term of patent 14 years.

To all whom it may concern:

Be it known that I, JAMES H. MARDOCK, a citizen of the United States, residing at Fruitland, in the county of Muscatine and State of Iowa, have invented and produced a new and original Design for a Napkin-Holder, of which the following is a specification.

This invention relates to a new and original design for a napkin-holder, and the essential feature resides in an arrow-shaped extremity with curved side edges having an intermediate body extending from the inner portion thereof and which is reduced in width and provided with parallel side edges, the extremity of the body opposite the arrow-shaped extremity being of rectangular contour.

In the drawings, Figure 1 is a perspective view of a napkin-holder embodying the features of the design. Fig. 2 is a bottom plan view of the same.

The numeral 1 designates an intermediate

elongated body having parallel side edges and provided at one end with a broadened arrow-shaped head or extremity 2 and a laterally-extending rectangular opposite extremity 3. 25 The under side of the body has a fixed bar thereon, as at 4, with an open inclined hook 5 at one end and a loop 6 at the other end, the hook and loop standing at an angle of inclination to the plane of the body. 30

Having thus described the invention, what is claimed as new is—

The design for a napkin-holder, herein shown and described.

In testimony that I claim the foregoing as 35 my own I have hereto affixed my signature in the presence of two witnesses.

JAMES H. MARDOCK.
